DESIGN FOR A FRYING PAN

Helen D. Ekonomon, New York, N. Y.

Application August 18, 1944, Serial No. 114,929

Term of patent 14 years

(Cl. D44—1)

To all whom it may concern:

Be it known that I, Helen D. Ekonomon, a citizen of the United States, residing at New York, in the county of New York and State of New York, have invented a new, original, and ornamental Design for a Frying Pan, of which the following is a specification, reference being had to the accompanying drawing, forming a part hereof.

In the drawing:

Fig. 1 is a perspective view of a frying pan, showing my new design; and

Fig. 2 is a top plan view of the same.

I claim:

The ornamental design for a frying pan, as shown.

HELEN D. EKONOMON.
